METHOD OF STITCHING FASTENER TAPE FOR FORMING FASTENER SECTIONS

Leo Roseman, Newark, N. J.

Application May 5, 1953, Serial No. 353,200

3 Claims. (Cl. 112—262)

This invention relates in particular to the manufacture of sections of adjustable fasteners to be used, for example, in connecting the rear end portions of brassieres or the like, each fastener section comprising a piece of fabric tape having one or more fastener elements such as hooks or eyes secured thereon and also having a short elastic strap projecting laterally from one longitudinal edge thereof, the end edges of the piece being bound by a line of stitches.

In the manufacture of such fastener sections heretofore, a long strip of fastener tape has been made with the elastic straps projecting therefrom in closely spaced relation longitudinally of the tape, and a buttonhole stitching machine has been used for stitching the tape transversely between adjacent elastic straps with the juxtaposed parallel lines of stitches running transversely of the tape and serving as the end bindings for the adjacent fastener sections to be formed, and then the long tape has been severed between said juxtaposed lines of stitches. During the formation of the buttonhole stitches, the needle must travel first in one direction transversely of and entirely across the strip of tape and then return in the reverse direction to form the opposed lines or rows of stitches; and this is a slow, unsatisfactory and expensive operation.

A prime object of the present invention is to save at least one half of the time now required to make said buttonhole stitches and to provide a more satisfactory and less expensive method of, and machine for, forming opposed lines or rows of stitches transversely of a strip of fastener tape of the character described, whereby a more rapid and economical production of fastener sections can be achieved. The stitches may be zig-zag stitches, straight stitches or other suitable stitches.

In the prior art, when a buttonhole machine was used, the surrounding buttonhole stitches were cut at the points of juncture of the elastic strap and the fastener strip when said strip was divided into fastener sections, and those cut stitches were thus permitted to unravel at the point where unravelling is most objectionable, and another object of my invention is to prevent such unravelling of stitches by making the stitches continuous at said points in a novel manner.

Moreover, with the buttonhole machines, it has been necessary to locate the fastener elements a substantial distance away from the end edges of the fastener sections so as to provide adequate clearance for placement of the tape with the fasteners thereon beneath the buttonhole machine needles so as to prevent accidental breaking of the needles should the operator misjudge the location of the fastener strip beneath the needle; and this has resulted in unsatisfactory fastener sections in that the fastener elements are located too far away from the end edges of the fastener sections. Therefore a further object of my invention is to provide a method which shall permit the fastener elements to be located close to the end edges of the fastener sections and at the same time eliminate the

2

possibility of accidental contact of the needles with the fastener elements.

Still another object of my invention is to provide such a method wherein a plurality of series of opposed rows of stitches transversely of the strip can be formed in one continuous operation. This is in contrast to the formation of the stitches for a buttonhole, the stopping of the needle, the subsequent feeding of the tape for the next buttonhole and the starting of the needle to form said buttonhole and so on which has been common in the use of buttonhole machines; and moreover, with my method the edge-binding stitches do not cross any severed portions as is the case when a zig-zag machine is used.

Further objects are to provide a method and apparatus for forming two parallel lines or rows of buttonhole-like stitches transversely of a fabric strip or the like which shall include the utilization of two needles arranged in side by side spaced relation, and the manipulation of said needles and the strip in such a way that one needle will form a line or row of stitches from one edge of the strip to a point intermediate the width of the strip while the other needle simultaneously forms a line or row of stitches beginning at a point between said edge of the strip and the first-mentioned point and extending to the other edge of the strip, after which the direction of relative movement of the parts is reversed and other similar lines of stitches are made in spaced relation to the first line; and to provide such a method and apparatus wherein each needle shall form a line of stitches longitudinally of the strip from one series to the next series of transverse lines of stitches.

Other objects, advantages and results of the invention will be brought out by the following description in conjunction with the accompanying drawings in which

Figure 1 is a schematic front elevational view of the stitching head of a sewing machine for performing the operations hereinbefore described;

Figure 2 is an end elevational view of the stitching head;

Figure 3 is a schematic and elevational view of the stitch forming mechanism and work showing the oscillating needles in one position;

Figure 4 is a similar view showing the oscillating needles in another position;

Figure 5 is a fragmentary composite perspective view of a strip of fabric and two needles and illustrating the beginning of the first step in the method of forming the stitches hereinbefore described;

Figure 6 is a similar view showing the next step in the formation of the stitches;

Figure 7 is a like view showing the next successive step;

Figure 8 is a view like Figure 7 showing the final step in the formation of the two parallel rows of stitches;

Figure 9 is a fragmentary plan view of a section of the fastener tape particularly contemplated by the invention showing the stitches formed in accordance with the invention; and

Figure 10 is a similar view showing the fastener tape severed into fastener sections.

Describing the fundamental principles of the invention and with particular reference to Figures 5 to 8 inclusive, the reference character A designates a strip of textile fabric or the like in which the stitches are formed by two needles B and C that during the performance of the method of the invention are spaced from each other transversely of the strip A so that one of the needles will be disposed closely adjacent one of the longitudinal edges 1 of the strip while the other needle will be disposed at approximately the central point in the width of the strip

or on the longitudinal median line of the strip as best shown in Figures 5 and 7.

The needles and strip A may be operated in any suitable manner, but are shown as mounted on the needle bar D of a sewing machine and the needles are threaded in the usual way (not shown). Where the stitches are to be of known straight lock-stitch type, the needle bar will be reciprocated in cooperation relative to the usual other elements of a stitch-forming mechanism so as to cause penetration of the strip by the needles and carrying of the needle thread through the strip for interlock with the locking or bobbin thread of the sewing machine to form the stitches that are generally designated 2. The strip A may be fed longitudinally beneath the needles along the bed plate of the sewing machine by the usual work feed mechanism (not shown), and at pre-determined times the strip may be moved transversely of itself by any suitable mechanical feeding mechanism (not shown) or by hand.

Assuming that Figure 5 illustrates the relative positions of the strip A and needles B and C at the beginning of an operation contemplated by the invention, it will be seen that one needle B is adjacent one longitudinal edge of the strip while the other needle C is approximately at the center of the width of the strip. The needles are then reciprocated simultaneously and the strip is moved transversely step by step in the direction of the arrow in Figure 6 so as to form a line of stitches transversely of the strip comprising two aligned groups of stitches a. Then the strip is moved a short distance longitudinally in the direction of the arrow in Figure 7 as indicated at b, after which the strip is moved transversely step by step in the direction opposite to that in which it was moved in Figure 6, as shown by the arrow in Figure 8 to form another line of stitches parallel to the first line and comprising longitudinally aligned groups of stitches c. Thereupon, the strip A is moved longitudinally and parallel lines of stitches d are formed along the longitudinal median line of the strip and along one edge of the strip respectively. This brings the needles back to the position shown in Figure 5, whereupon another series of transverse stitches may be formed in the same manner as above described.

The strip A may then be severed between the groups a and c of the respective series of transverse stitches so as to form sections. It will be understood that if desired, to limit unraveling of the fabric or the sets of stitches at the ends of the respective sections, superposed or tying stitches e may be formed at one or both ends of the sets of stitches a and c by proper relative movement of the needles and work.

At this point it should be noted that either the strip A may be moved transversely as described or the needles could be oscillated transversely of the strip in forming the stitches above described.

Obviously the stitches d are not important to the separation and binding of the fastener sections, but they do permit the formation of the plurality of series a, c of transverse stitches successively in a continuous operation, whereupon the fastener sections can be produced rapidly and economically.

Where fastener sections of the type including pieces of fabric and elastic straps are to be produced, it is desirable that the transverse stitches be of the zig-zag type as shown in Figures 9 and 10. Here the strip E of fabric has fastener elements, particularly wire eyes 3, secured theron and also has a plurality of elastic straps 4 secured to and projecting from one longitudinal edge of the strip in spaced relation to each other. The transverse lines of stitches f and g that correspond respectively to the stitches a and c are disposed in approximate alignment with and penetrate the adjacent longitudinal edge portions of the elastic straps 4 so as to fasten the straps to the strip and are of the zig-zag type so as to form neat and firm edge bindings for the fastener sections F when

they are severed from the strip between the transverse stitches f and g, as shown in Figure 10.

The zig-zag stitches may be produced by any suitable mechanism which is schematically illustrated in Figs. 1 to 4 inclusive and is of the same general type disclosed in Patent No. 2,153,006 granted on April 4, 1939 to Leo Roseman. The needle bar D is mounted in a bracket G which is pivotally mounted at 5 on the frame H of the stitching head of the machine. The needle bar is reciprocated in the bracket G in the usual way from the drive shaft I of the machine, and as shown, the shaft I carries a disk K on which is a wrist pin that is connected by a link to a pin on the needle bar (not shown) but illustrated in said Patent No. 2,153,006.

15 The needle bar is oscillated back and forth as indicated by the arrows in Figure 2, and at the same time the work is manipulated transversely of itself along the bed plate L in short steps to form the zig-zag stitches f, g, it being understood by those skilled in the art that any suitable mechanism, generally controlled by a cam, could be utilized for so manipulating the work. For oscillating the needle bar, a link 6 is pivotally connected to the bracket G and is reciprocated by a cam (not shown but generally illustrated in said Patent No. 2,153,006).

20 It will be understood by those skilled in the art that the stitch groups of each set of stitches a and c may overlap each other or be spaced apart at the center of the width of the strip, as desired and as shown. Where fastener sections of the type shown in Figures 9 and 10 are to be made, probably it is better to have the groups of stitches of each set slightly overlap each other to make in effect a continuous line or row of stitches.

25 When desired, for example, when there are three rows of fastener elements, the needles can be spaced apart a distance less than one half the width of the fastener strip E so that the longitudinal line of stitches intermediate the width of the strip will not have to pass over the middle row of fastener elements. Under such conditions, one needle would travel from one edge of the strip about two-thirds of the width of the tape toward the other edge while the other needle would simultaneously move from a point spaced about one-third of the width of the tape from the first-mentioned edge to the second mentioned edge of the tape, the groups of stitches thus formed overlapping each other for about one-third the width of the tape. However, instead of that method, a known type of stitch-over machine could be used to permit the stitches to traverse the fastener elements and yet prevent the needle from striking said elements.

30 When the fastener strip is cut transversely to form the fastener sections it is desirable to leave a portion of the strip, for example $\frac{1}{16}$ of an inch of the width thereof uncut, so that the plurality of fastener sections can be handled in a strip as a unit until it is desired to separate them from each other. The fastener sections in this strip condition can be more readily fed to sewing machines for attaching the fastener sections to garments. When it is desired, the sections can be completely separated by simply snipping the uncut portions of the strip.

35 It will thus be seen that the method of the invention makes possible entirely automatic production of fastener sections of the character described with relatively unskilled operators; one operator can easily attend to three to five machines whereby production of the fastener sections can be increased six to ten times of that heretofore achieved with the buttonhole and other prior art machines. Moreover, the invention permits the rapid and efficient production of fastener strips of greater width than possible with the known button hole machines which are generally limited to lines of stitches up to two inches in length. Fastener sections having three rows of fastener elements should be at least $2\frac{1}{4}$ inches in width so that the button hole machines would not be capable of producing such fastener sections.

40 75 Modifications and changes in the steps of the method

will occur to those skilled in the art as within the spirit and scope of the invention, and it will also be clear that other types of apparatus or machines than that described may be used in practicing the invention.

I claim:

1. In a method of making fastener sections from a long tape having fastener elements spaced longitudinally thereof and extending toward one longitudinal edge of the tape, and elongate straps projecting perpendicularly from the other longitudinal edge of the tape with the juxtaposed longitudinal edges of two adjacent straps disposed in spaced relation to each other and between two adjacent fastener elements, the steps consisting in arranging at least two needles in parallel relation spaced apart equidistantly transversely of the tape and in cooperative relation to other elements of a stitch-forming mechanism with one needle disposed above one longitudinal edge of the tape between two adjacent fastener elements and with the other needle disposed intermediate the width of the tape, relatively moving the needles and the tape in the direction of spacing of said needles and transversely of the tape with the tape beneath said needles until the second-mentioned needle is disposed above the opposite longitudinal edge of the tape and simultaneously reciprocating said needles into and out of said tape during said relative movement of the tape and the needles and causing each needle to form one line of stitches in continuation of the line of stitches formed by the other needles, thus providing at the same time a plurality of aligned lines of stitches extending transversely of the tape from edge to edge thereof between said adjacent fastener elements

and along the edge of one of said straps, then relatively moving the tape and the needles longitudinally of the tape a distance less than the distance between said two fastener elements while reciprocating the needles, and thereafter relatively moving the tape and the needles transversely in the direction opposite to that of the first-mentioned transverse movement while reciprocating said needles until the first-mentioned needle is again disposed above the first-mentioned longitudinal edge of the tape between said two fastener elements to form a plurality of other aligned lines of stitches each produced by one needle between said two fastener elements and along the adjacent edge of the other of said two straps.

5 15 20 25 30 20 15 20 25 30

2. In a method as defined in claim 1, oscillating said needles in directions longitudinally of the tape simultaneously with the reciprocation of the needles and simultaneously with the relative movement of the work and the needles transversely of the tape to form zig-zag stitches to serve as a binding for the edge of a tape section after the tape has been severed between said transverse lines of stitches.

3. In a method as defined in claim 2, causing said zig-zag stitches to penetrate the edge portions of said two straps to secure the straps to the tape.
